UNITED STATES PATENT OFFICE.

ALBERT W. ERDMAN, OF DERBY, CONNECTICUT, ASSIGNOR TO THE DRIGGS-SEABURY GUN AND AMMUNITION COMPANY, OF NEW YORK, N. Y.

ADJUSTABLE STOP FOR CONTROLLING BREECH MECHANISMS OF AUTOMATIC OR SEMI-AUTOMATIC GUNS.

SPECIFICATION forming part of Letters Patent No. 665,199, dated January 1, 1901.

Application filed October 18, 1900. Serial No. 32,975. (No model.)

To all whom it may concern:

Be it known that I, ALBERT W. ERDMAN, a citizen of the United States, residing at Derby, in the county of New Haven and State of Connecticut, have invented certain new and useful Improvements in Adjustable Stops for Controlling the Breech Mechanism of Automatic or Semi-Automatic Guns; and I do hereby declare the following to be a full, clear, and exact description of the invention, such as will enable others skilled in the art to which it appertains to make and use the same.

My invention relates to improvements in mechanism for operating the breech-closure of automatic or semi-automatic guns; and it especially relates to guns of that class in which the breech-closure is controlled by the action of a vibrating lever carried by or moving with the gun during the recoil and counter-recoil. 15 This invention relates more particularly to an adjustable camming device adapted to engage the breech-operating lever on counter-recoil, but to yield to the said lever during the recoil of the gun.

20 This invention is especially applicable to guns of the type shown in the patent to William H. Driggs and Vernon C. Tasker, No. 625,326, granted May 23, 1899, and reference may be made to this patent for the various operative parts of the gun therein shown, but which do not form a part of my present invention, and hence are not shown herein.

Reference is had to the accompanying drawings, in which the same parts are indicated 35 by the same letters throughout the several views.

Figure 1 shows a part of the breech of the gun with part of the gun broken away to show the right-hand portion of the slide. Fig. 2 40 represents a section along the broken line 22 of Fig. 1, parts being shown in elevation. Fig. 3 is a detail view showing a part of the slide and the plate in which the cam is mounted. Fig. 4 is a detail showing the opposite 45 side of the device shown in Fig. 3. Fig. 5 is a detail showing the arm on the operating-shaft for automatic or semi-automatic firing, and Fig. 6 is a perspective view of the cam-piece as detached from the rest of the apparatus.

A represents the body of the gun, which projects downward, as at A', and at A² forms a bearing for the operating-shaft D, by means of which the breech-lock is moved from the closed to the open position, or vice versa. 55 This operating-shaft also carries a hand-lever D' for hand operation, and to this hand-lever the rod E is connected, which rod is spring-constrained, as by the spring E', indicated in Fig. 1 and shown fully in the patent to Driggs and Tasker aforesaid and well known in the art.)

The gun is provided with dovetail rib a to slide in the guideway of the slide B. This slide is preferably provided with downwardly-projecting arms B², to which the plates G and C are secured. The latter might be made integral with the former or with the slide; but for convenient manufacture it is preferable to make the same separate therefrom. Moreover, the particular form of the arms B² is not important, as any suitable bearing on the slide for the plates G and C might be provided. The plate C is recessed, as shown in Fig. 4, and is provided with a stop-lug C' and a face c'. The operating-shaft D is provided at the end opposite to the hand-lever with two arms D² and D³, from which project the lugs d² and d³, respectively. (See Figs. 2 and 5.) These lugs control the automatic or semi-automatic firing of the gun, as will be hereinafter described.

The plate G has integral therewith or attached thereto a sleeve G', and in this sleeve is journaled a shank F' of the cam-piece F, 85 which cam-piece carries the stop F² and the locking-lug F³. The stop F² has a yielding face f, a holding-face f', and a releasing-face f², while the locking-lug F³ has a holding-face f³. The spring K (see Fig. 2) normally 90 presses the face f⁴ of the cam-piece against the face c' of the lug C' (see Figs. 1 and 4) and thus normally holds the cam in the operative position.

So as to be able to throw the cam out of engagement when it is desired to operate the gun by hand I provide a handle H', fast to the shank F' of the cam-piece F, and in this shank I secure a spring H², as at h², which spring bears on the pawl H³, which is pivot- 100

ed at h^3 and serves to hold the same in two positions, just as a spring in a pocket-knife holds the blade in two positions. A slot g' (see Fig. 3) is provided in the sleeve G' , and if the handle H' be turned slightly to the right, as at Fig. 3, and then this pawl h^3 be pressed down to engage in the slot g' the spring H^2 will hold it there until it is released by hand, and at the same time this pawl will hold the lug F^2 down clear of the operating-lug d^2 and the automatic or semi-automatic attachment will be out of engagement and the gun may be operated by hand in the usual way.

15 The operation of the device is as follows: Suppose the parts to be in the position shown in Figs. 1, 2, and 4 and the gun to be fired. The recoil of the gun will cause the lug d^2 to strike the cam-face f , pressing the cam down 20 against the action of the spring K until this lug d^2 has passed in rear of the cam, and the cam being released will spring up again in the position shown in Figs. 1 and 4. The gun will then continue its further recoil, but 25 on returning to its initial position the lug d^2 will strike the holding-face f' of the cam and the cam not being able to yield the arm D^2 is swung rearward, rotating with operating-shaft D and opening the breech of the gun. 30 When the breech of the gun has been fully opened, the lug d^2 will pass beneath the releasing-face f^2 of the cam as the gun continues its return to the initial position and the spring attached to the rod E will close the breech mechanism, as happens in ordinary firing. Where it is desired to fire automatically or semi-automatically an automatically-controlled stop is required to hold the breech-block in an open position; but such 40 stops are well known in the art—such, for instance, as the extractor-stop shown in the patent to Driggs and Tasker aforesaid.

When the automatic or semi-automatic attachment is in operation or when the cam F' is in the operative position, it will be impossible to operate the breech mechanism by hand, because if the hand-lever be rotated the lug d^2 will promptly bring up against the holding-face f^3 of the lug F^2 on the cam-piece 45 F and the further motion of the hand-lever will cease.

My invention does not relate to anything more than the mechanism for operating the main shaft automatically or semi-automatically and for releasing said mechanism, so that the gun may be operated by hand when desired, and therefore the various well-known details are omitted—such as the trunnions for the slide, the gun-mount proper, the 55 mechanism for closing the breech when the spring-constrained arm has been released from engagement with the cam, &c.

While for convenience of description I have shown this invention as applied to a 60 gun-mount of the type shown in the patent

to Driggs and Tasker aforesaid, I do not mean to confine myself to the details of that particular mount or of any particular mount or of any particular breech-closure, the invention being applicable to almost any of the 70 types of breech-closures in which the breech-block is moved by an oscillating lever and in which it is desired to automatically operate that lever on the counter recoil of the gun.

Having thus described my said invention, what I claim, and desire to secure by Letters Patent of the United States, is—

1. In a gun, the combination with a rock-shaft for operating the breech mechanism, a spring-constrained arm secured to or integral 80 with said rock-shaft provided with an engaging lug and a stop-lug, and a rotary cam-piece having a stop to engage said engaging lug, and a locking-lug to engage said stop-lug, with means for rotating said cam-piece 85 and for throwing the latter part out of engagement, when desired, substantially as described.

2. In a gun, the combination with a rock-shaft for operating the breech mechanism, a 90 spring-constrained arm secured to or integral with said rock-shaft provided with an engaging lug and a stop-lug, and a rotary cam-piece having a stop to engage said engaging lug, and a locking-lug to engage said stop-lug, and a handle and spring-catch for rotating 95 said cam-piece and holding the same in the disengaged position when desired, substantially as described.

3. In a gun, the combination with a rock-shaft for operating the breech mechanism, a spring-constrained arm secured to or integral 100 with said rock-shaft provided with an engaging lug and a stop-lug, and a rotary cam-piece having a stop to engage said engaging lug and a locking-lug to engage said stop-lug, a spring normally holding said cam-piece in the engaging position, and means for rotating 105 the cam-piece and for throwing the parts out of engagement when desired, substantially as described.

4. In a gun, the combination with a rock-shaft for operating the breech mechanism, a spring-constrained arm secured to or integral 110 with said rock-shaft provided with an engaging lug and a stop-lug, and a rotary cam-piece in the form of a bell-crank having a stop to engage said engaging lug, and a locking-lug to engage said stop-lug, a shank secured to or integral with said cam-piece and 115 journaled in the gun-mount, with means for rotating said shank and for throwing the stop out of engagement, when desired, substantially as described.

5. In a gun, the combination with a rock-shaft for operating the breech mechanism, a spring-constrained arm secured to or integral 120 with said rock-shaft provided with an engaging lug and a stop-lug, and a rotary cam-piece in the form of a bell-crank having a stop 125

130

to engage said engaging lug, and a locking-lug to engage said stop-lug, and a shank secured to or integral with said cam-piece and journaled in the gun-mount, and a handle and spring-catch for rotating said shank and holding the same in the disengaged position, when desired, substantially as described.

In testimony whereof I affix my signature in presence of two witnesses.

ALBERT W. ERDMAN.
